Primary Examiner — Mitchell Siegel

(74) Attorney, Agent, or Firm — Morgan, Lewis & Bockius LLP

(57) **CLAIM**

The ornamental design for a forklift, as shown and described.

DESCRIPTION

FIG. 1 is a front elevation view of a forklift embodying the first inventive design;

FIG. 2 is a rear elevation view of FIG. 1 embodying a first inventive design;

FIG. 3 is a left side elevation view of FIG. 1 embodying the first inventive design;

FIG. 4 is a right side elevation view of FIG. 1 embodying the first inventive design;

FIG. 5 is a top elevation view of FIG. 1 embodying the first inventive design;

FIG. 6 is a stereogram view of FIG. 1 embodying the first inventive design;

FIG. 7 is another stereogram view of FIG. 1 embodying the first inventive design; and,

FIG. 8 is another stereogram view of FIG. 1 embodying the first inventive design.

1 Claim, 8 Drawing Sheets(56)
